(57) **CLAIM**

The ornamental design for a packaging label on a bottle, as shown and described.

DESCRIPTION

The file of this patent contains at least one photograph executed in color. Copies of this patent with color photograph(s) will be provided by the Office upon request and payment of the necessary fee.

FIG. 1 is a front elevation view of the packaging label on the bottle showing our new design, wherein the rear elevation view, right side elevation view and left side elevation view are mirror images of this view; and,

FIG. 2 is a top view of thereof.
